UNITED STATES PATENT OFFICE.

GEORGE LIVINGSTON HENDERSON, OF YELLOWSTONE PARK, WYOMING.

RIFLE.

1,322,438.

Specification of Letters Patent.

Patented Nov. 18, 1919.

Application filed November 16, 1918. Serial No. 262,825.

To all whom it may concern:

Be it known that I, GEORGE L. HENDERSON, a citizen of the United States, and a resident of Yellowstone Park, in the county 5 of Yellowstone National Park and State of Wyoming, have invented a new and Improved Rifle, of which the following is a full, clear, and exact description.

The invention relates to magazine hand 10 firearms and its object is to provide a new and improved rifle having an exceedingly simple operating device not liable to get easily out of order. Another object is to providing a rifle for use by cavalrymen, 15 mounted police and other persons, and arranged to permit of readily placing the rifle in a saddle scabbard. Another object is to prevent accidental firing of the gun on failing to return the operating lever 20 to full closed position.

With these and other objects in view, the invention consists of certain novel features of construction as hereinafter shown and described and then specifically pointed 25 out in the claims.

A practical embodiment of the invention is represented in the accompanying drawings forming a part of this specification, in which similar characters of reference 30 indicate corresponding parts in all the views.

Figure 1 is a side elevation of the rifle with the breech block in closed position;

Fig. 2 is a similar view of the same with 35 parts in section and with the breech block retracted;

Fig. 3 is a cross section of the same on the line 3—3 of Fig. 1;

Fig. 4 is a plan view of the rifle with parts 40 in section and with the breech block in closed position;

Fig. 5 is a longitudinal section of the same on the line 5—5 of Fig. 4;

Fig. 6 is a similar view of the same with 45 the breech block in retracted position;

Fig. 7 is a plan view of the rifle with parts in section and the breech block in closed position;

Fig. 8 is a similar view of the same with 50 the breech block in retracted position;

Fig. 9 is a cross section of the same on the line 9—9 of Fig. 2;

Fig. 10 is a sectional plan view of the same on the line 10—10 of Fig. 1;

Fig. 11 is a sectional side elevation on 55 the line 11—11 of Fig. 7;

Fig. 12 is a cross section of the same on the line 12—12 of Fig. 1;

Fig. 13 is a perspective view of the breech 60 block and its carrier;

Fig. 14 is a similar view of the sides of the breech block carrier with the bearings for the breech block removed;

Fig. 15 is a perspective view of the breech 65 block; and

Fig. 16 is a similar view of the firing pin.

The frame 20 of the firearm is provided at the rear end with a stock 21 and on the forward end with a barrel 22 adapted to 70 receive cartridges 23 held in a magazine 24 attached to the frame 20, the cartridges being preferably arranged in staggered relation, as plainly shown in Fig. 12. The two lowermost cartridges 23 in the magazine 24 rest on a follower 25 pressed upwardly by a spring 26 seated on the bottom 27 of the magazine 24. 75

The frame 20 is provided at the sides with longitudinally extending guideways 80 30, 31, in which are mounted to slide the sides 32 and 33 of a breech block carrier 34 in which is mounted to turn a breech block 35 containing a firing pin 36 pressed on by a spring 37 and serving to fire the 85 cartridge in the barrel 22, as hereinafter more fully explained. The forward end of the breech block 35 is provided with cam lugs 40, 41 adapted to engage recesses 42, 43 formed in the forward end of the frame 90 20 adjacent the rear end of the barrel 22. The recesses 42 and 43 have beveled forward walls (see Fig. 6) to draw the forward end of the breech block 35 against the seat 44 formed on the frame 20 to hold 95 the breech block firmly seated and locked when in forward position. The breech block 35 is provided near its rear end with a lug 45 adapted to engage a locking recess 46 formed in the rear portion of the 100 frame 20 to assist the lugs 40 and 41 to hold the breech block in locked position in the carrier 34.

In order to impart a forward and backward sliding movement to the breech block 105 carrier 34 use is made of an operating lever 50 pivotally connected at its upper end with a pivot 51 arranged in the side 33 of the

breech block carrier 34. The operating lever 50 is provided at its lower end with a handle 52, and intermediate the handle 52 and the pivot 51 is arranged an arcuate slot 53 into which projects the wrist pin 54 of a crank arm 55 having a transverse shaft or pivot 56 mounted to turn in the frame 20. The back of the lever 50 abuts against a friction roller 57 journaled on the frame 20 to ease the movement of the lever 50. It will be noticed that by the arrangement described the operator having hold of the handle 52 can actuate the lever 50 with a view to slide the breech block carrier 34 forward or backward on the frame 20. The breech block 35 is given a quarter turn in the breech block carrier 34 and for this purpose a mechanism is provided controlled by the lever 50 and arranged as follows: On the pivot or shaft 56 is secured a segmental gear wheel 60 in mesh with teeth 61 formed on one side of a rack 62 mounted to slide up and down in a guideway 63 (see Fig. 3) formed in the rear portion of the frame 20. The upper end of the slide 62 is provided on its face with gear teeth 64 in mesh with gear teeth 65 formed on one side of the breech block 35 adjacent the rear lug 45, as plainly indicated in Figs. 4 and 7. It will be seen that when the breech block carrier 34 and with it the breech block 35 is moved forwardly by the operator swinging the handle 52 of the actuating lever 50 rearwardly and upwardly then the teeth 65 of the breech block 35 move into engagement with the teeth 64 on the rack 62. During this forward movement of the breech block carrier 34 and the breech block 35 the slot 53 of the lever 50 travels along the wrist pin 54 and when the breech block carrier reaches its forward position then the wrist pin 54 is at the end of the slot 53 and the operator now swings the handle 52 farther upward with the pivot 51 as the fulcrum instead of the wrist pin 54. During this final upward movement of the actuating lever 50 an upward swinging movement is given to the crank arm 55 whereby the pivot 56 and the segmental gear wheel 60 are turned and the turning movement of the gear wheel 60 causes the rack 62 to slide upward whereby the teeth 64 of the rack 62 in mesh with the teeth on the breech block 35 turn the latter to engage the lugs 40 and 41 with the recesses 42, 43 and to engage the lug 45 with the recess 46 thus locking the breech block carrier in its forward position and with it the breech block 35. It is understood that during this turning movement of the breech block 35 the latter is drawn forwardly in firm engagement with its seat 44 by the action of the cam lugs 40, 41 and 45 on the beveled walls of the recesses 42, 43 and 46. It is also understood that during this forward move-

ment of the breech block carrier 34 and the breech block 35 the latter pushes the uppermost cartridge 23 into the barrel 22 while the next following cartridge is pressed in contact with the under side of the breech block by the action of the spring-pressed follower 25. When it is desired to open the rifle for reloading or other purposes the handle 52 of the actuating lever 50 is swung downward on the pivot 51 as the fulcrum 75 whereby a downward swinging movement is given to the crank arm 55. When this takes place a downward swinging movement is given to the segmental gear wheel 60 which on account of being in mesh with the teeth 61 of the rack 62 moves the latter downward whereby the teeth 64 of this rack 62 in engagement with the teeth 65 turn the breech block back to its original position, that is, with the lugs 40, 41 and 45 out of engagement with the recesses 42, 43 and 46. During the further downward and forward swinging movement given to the handle 52 the lever 50 is turned on the wrist pin 54 as the fulcrum whereby the breech block carrier 34 and with it the breech block 35 are moved rearwardly into open position. It is understood that when the breech block is turned to the position for retraction its lugs 40, 41 and 45 extend sidewise and hence 95 are in alignment with the guideways 30, 31. The rack 62 is provided in its lower back portion with a guideway 67 into which projects a guide lug 68 attached to or forming part of the frame 20 to guide the rack 100 62 in its up and down movement and to limit the downward movement of the said rack 62.

The firing pin 36 is provided on the right-hand side with a sidewise extending lug 70 105 extending through an opening 71 formed in the breech block 35 and the said lug 70 is adapted to pass into a guideway 72 formed on the inner face of the side 33 of the breech block carrier 34 (see Figs. 3 and 8). By the 110 arrangement described, the firing pin 36 is held against turning with the breech block 35 and is free to slide longitudinally independent of the breech block 35. The lug 70 of the firing pin 36 is provided with a 115 depending lug 73 adapted to be engaged by a shoulder 80 of a sear 81 mounted to slide up and down in a bearing 82 formed in the frame 20. The under side of the sear 81 is pressed on by a spring 83 to move the 120 sear 81 in an upward direction. The sear 81 is provided at its rear side with a notch 84 into which projects an arm 85 of a trigger 86 fulcrumed at 87 on the frame 20, the lower end of the trigger extending in 125 the rear of the actuating lever 50. On pressing the trigger 86 rearwardly the sear 81 is caused to slide downward to disengage the shoulder 80 from the lug 73 to allow the firing pin 36 to move forward by the action 130

of its spring 37 to fire the cartridge 23 held in the barrel 22 at the time. The forward wall of the opening 71 in the breech block 35 forms a shoulder 88 extending into the 5 path of the lug 73 at the time the breech block is in its normal position, that is, with its locking lugs 40, 41 and 45 extending sidewise, and hence when the breech block 35 is moved into closed position prior to turning 10 it then the shoulder 88 is in the path of the lug 73 (see Fig. 11), and should the trigger 86 now be accidentally actuated and with it the sear 81 to release the lug 73 and the firing pin 36 then the latter can only move 15 forward a short distance, that is, until the lug 73 abuts against the shoulder 88. Thus the firing pin is not liable to fire a cartridge unless the breech block is turned previously into locking position as above explained. It 20 is understood that when the breech block is turned into this locking position the shoulder 88 moves out of the path of the lug 73 to allow the firing pin 36 to move forward to its full stroke to fire the cartridge in the 25 barrel 22.

In order to lock the trigger 86 against movement the following arrangement is made: The trigger 86 is provided at one side with a recess 90 (see Fig. 9) and in this 30 recess is adapted to pass a bolt 91 mounted to slide in a guideway 92 formed in the stock 21. The bolt 91 is pivotally connected by a link 93 with a lug 94 depending from a safety slide 95 mounted to slide in a suitable 35 bearing 96 attached to the top of the stock 21. The forward end of the slide 95 is adapted to be engaged by a head 97 formed on the rear end of the breech block 35 to move the slide 95 rearwardly on moving the 40 breech block carrier 34 and with it the breech block 35 into rearward open position. The safety slide 95 is provided on its under side with a recess 100 adapted to be engaged by a lug 101 of a spring 102 fastened 45 at its rear end to the stock 21. The forward end of the spring catch 102 is provided with a cam 103 adapted to be engaged by the head 97 to swing the spring catch 102 downward with a view to disengage its lug 101 50 from the recess 100 at the time the head 97 of the breech block 35 is moved into rearward position. By the arrangement described the slide 95 is unlocked prior to the head 97 pushing it rearward as above explained. The slide 95 is provided with a 55 fingerpiece 110 resting on the top of the spring catch 102 and normally projecting slightly above the slide 95 so that the operator on pressing the fingerpiece 110 downward causes the spring catch 102 to swing downward. When this takes place the lug 101 disengages the recess 100 to allow of pushing the slide 95 rearwardly by the operator. The fingerpiece 110 is provided in its back 60 with a recess 111 into which projects a pin

112 held on the slide 95 to limit the up and down movement of the fingerpiece 110. It is understood that when the slide 95 is moved rearwardly either by the breech block or by hand then the bolt 91 is withdrawn 70 from the recess 90 of the trigger 86 to allow the operator to pull the trigger for firing as above described. The forward end of the breech block carrier 34 is provided with a suitable extractor 120 (see Fig. 7) adapted 75 to engage the annular notch 121 of the cartridge 23 to pull the shell out of the barrel on retracting the said breech block carrier 34. The breech block 35 is provided with a suitable ejector 125 (see Fig. 5), preferably 80 in the form of a spring-pressed pin, adapted to engage the back of the cartridge 23 to throw the same sidewise out of the frame 20 on retracting the breech block carrier 34 and the breech block 35. 85

The operation is as follows: When the several parts are in the position shown in Figs. 1, 3, 4, 5 and 7 and a cartridge is in the barrel 22 and the trigger 86 is locked by the safety slide then the rifle cannot be 90 fired, and in order to fire it is necessary for the operator first to press the fingerpiece 110 to disengage the spring catch 102 from the safety slide 95 to allow the operator to push the latter rearwardly on the guideway 96. 95 By this movement of the safety slide 95 the bolt 91 is withdrawn from the recess 90 of the trigger 86 thus unlocking the trigger and allowing the operator to pull the same. When the trigger is pulled the sear 81 is 100 moved downward against the tension of its spring 83 and the shoulder 80 of the sear now disengages the lug 73 thereby releasing the firing pin 36 which is now pushed forward by the action of its spring 37 to fire the cartridge 23 in the barrel 22. The trigger 86 is released immediately after the firing and the operator now takes hold of the handle 52 of the actuating lever 50 and swings the same downward to actuate the rack 62 as previously explained with a view to turn the breech block 35 in the carrier 34 and thereby unlocking the breech block relative to the frame 20. On a further downward swinging movement given to the actuating lever 110 115 50 the breech block carrier 34 is retracted and with it the breech block 35. During this rearward movement of the breech block carrier 34 and the breech block 35 the empty shell is pulled out of the barrel 22 by the 120 extractor 120 and the shell is thrown sidewise through the opening above the magazine 24 by the action of the ejector 125. The uppermost cartridge 23 in the magazine 24 now moves in position in front of the retracted breech block 35 to be pushed forward into the barrel 22 on the next forward movement given to the breech block carrier 34 and the breech block 35. It is understood 125 that the breech block carrier 34 and the 130

breech block 35 are moved forward into closed position on swinging the actuating lever 50 into closed position, that is, swinging the handle 52 upward and rearward, and when the breech block carrier reaches the end of its forward movement then a further closing movement given to the lever 50 turns the breech block 35 to engage the lugs 40, 41 and 45 with the corresponding recesses 42, 43 and 46 to lock the breech block in place. The trigger 86 is next pulled to again fire the rifle. When it is desired to lock the rifle against firing it is only necessary for the operator to push the safety slide 95 forward on its guideway 96 to re-engage the bolt 91 with the recess 90 in the trigger 86 to lock the latter against movement. It will be noticed that should the operator fail to swing the handle 52 into complete final closed position, as shown in Fig. 1, then the breech block 35 is not turned in the breech block carrier 34 and hence the shoulder 88 remains in the path of the lug 73 and firing pin 36, and should the trigger 73 now be pulled and the firing pin released by the sear 81 then the firing pin can only move a short distance forward, that is, until the lug 73 strikes the shoulder 88. When the firing pin is in this position its front end is a distance from the cartridge 23 and hence the latter is not fired unless the breech block is turned in the breech block carrier and locked in place, as above explained. From the foregoing it will be seen that accidental firing of the gun is not liable to take place unless the breech block is in closed locked position. When the actuating lever 50 is in closed position then the rifle has no unduly projecting parts and hence it can be readily carried in a saddle scabbard.

It is understood that the cam lugs 40, 41 of the breech block 35 in coacting with the beveled walls of the recesses 42 and 43 draw the breech block 35 forward a short distance (say $\frac{3}{16}$ inch) when moving into locking position, and when the breech block is turned back out of locking position it is moved bodily rearward by the action of the cam lugs and the inclined walls of the recesses to cause the forcible removal of any shell that is liable to stick in the barrel by the action of the extractor 125.

Having thus described my invention, I claim as new and desire to secure by Letters Patent:—

1. In a rifle, an operating lever mounted to swing forward and backward and slide up and down, a breech block carrier mounted to slide forward and backward and pivotally connected with the said operating lever, a breech block mounted to turn in the said carrier and moving bodily with the same, and turning mechanism actuated from the said operating lever and connected with the said breech block to turn the latter into

locking position after the carrier reaches a forward position or to turn the breech block into an unlocked position prior to retracting the breech block carrier by the operating lever.

70

2. In a rifle, a frame, an operating lever mounted to swing forward and backward and to slide up and down on the said frame, a breech block carrier mounted to slide forward and backward on the said frame and pivotally connected with the said operating lever, a breech block mounted to turn in the said carrier and to move bodily therewith, coacting locking means on the said breech block and frame to lock the breech block and its carrier against sliding on turning the breech block when the carrier reaches a forward position, and turning means for turning the breech block into locking or unlock- 80 ing position and controlled by the said operating lever.

75

3. In a rifle, a frame, a barrel attached to the frame, a breech block carrier mounted to slide forward and backward on the said frame, a breech block mounted to turn in the said carrier and moving bodily therewith, coacting locking means between the said breech block and frame to lock the breech block in place when the carrier is in forward position, an operating lever pivotally connected with the said breech block carrier to move the latter forward or backward, a crank arm fulcrumed on the said frame and on which the said operating lever is mounted to swing and to slide, and turning means controlled by the said crank arm and connected with the said breech block to turn the latter when the said carrier is in forward position.

85

4. In a rifle, a frame, a barrel attached to the frame, a breech block carrier mounted to slide forward and backward on the said frame, a breech block mounted to turn in the said carrier and moving bodily therewith, coacting locking means between the said breech block and frame to lock the breech block in place when the carrier is in forward position, an operating lever pivotally connected with the said breech block carrier to move the latter forward or backward, a crank arm fulcrumed on the said frame and on which the said operating lever is mounted to swing and to slide, a rack mounted to slide up and down on the said frame and provided with two sets of teeth, rack teeth on the said breech block and engaging one set of teeth on the rack at the time the breech block carrier is in forward position, and rack teeth on the said crank arm and engaging the other set of teeth on the rack.

90

5. In a rifle, a frame provided with locking means, a barrel attached to the frame, a breech block carrier mounted to slide forward and backward on the said frame, a breech block adapted to close the rear end of the barrel and mounted to turn in the said

10

breech block carrier and to move bodily with the same, the breech block having locking lugs adapted to engage or disengage the said locking recesses on turning the breech block, 5 a lever pivotally connected with the said breech block carrier and provided with a slot, a crank arm fulcrumed on the frame and having a wrist pin engaging the said lever slot, a segmental gear wheel turning 10 with the said crank arm, a rack mounted to slide up and down in the said frame and having rack teeth at its upper and lower ends, the lower rack teeth being in mesh with the said segmental gear wheel, and gear 15 teeth on one side of the breech block and in mesh with the upper rack teeth on the said rack.

6. In a rifle, a frame provided with spaced front and rear locking recesses, a barrel attached to the frame and having its axis in alinement with the axes of the said recesses, a breech block carrier mounted to slide on the said frame, a breech block mounted to bodily move with and to turn in the said carrier, the breech block being provided with front and rear cam lugs adapted to engage the said recesses on turning the breech block at the time the carrier is in forward position, a lever under the control of the operator and 20 pivotally connected with the said breech block carrier, the lever having an arcuate slot, a crank arm fulcrumed on the said frame and having its wrist pin engaging the said slot, a rack vertically movable on the 25 said frame, a segmental gear wheel turning with the said crank arm and in mesh with the said rack and teeth on the breech block and in mesh with the said rack, a spring-pressed firing pin slidable in the said 30 breech block and provided with a lug, the breech block having a side opening for the passage of the said lug, a guideway on the breech block carrier engaged by the said firing pin lug to hold the firing pin against 35 turning on turning the breech block, a sear engaging the said firing pin lug, and a trigger controlling the said sear.

with the said crank arm and in mesh with the said rack, and teeth on the breech block and in mesh with the said rack.

7. In a rifle, a frame provided with spaced front and rear locking recesses, a barrel attached to the frame and having its axis in alinement with the axes of the said recesses, a breech block carrier mounted to slide on the said frame, a breech block mounted to bodily move with and to turn in the said carrier, the breech block being provided with front and rear cam lugs adapted to engage the said recesses on turning the breech block at the time the carrier is in forward position, a lever under the control of the operator and pivotally connected with the said breech block carrier, the lever having an arcuate slot, a crank arm fulcrumed on the said frame and having its wrist pin engaging the said slot, a rack vertically movable in the said frame, a segmental gear wheel turning with the said crank arm and in mesh with the said rack and teeth on the breech block and in mesh with the said rack, a spring-pressed firing pin slidable in the said breech block and provided with a lug, the breech block having a side opening for the passage of the said lug, a guideway on the breech block carrier engaged by the said firing pin lug to hold the firing pin against turning on turning the breech block, a sear 40 engaging the said firing pin lug, and a trigger controlling the said sear. 45

GEORGE LIVINGSTON HENDERSON.
